Primary Examiner — Dominic Simone(74) *Attorney, Agent, or Firm* — Sheridan Ross P.C.(57) **CLAIM**

The ornamental design for a cycling shoe, as shown and described.

DESCRIPTION

FIG. 1 is a top plan view of a cycling shoe design showing our new design;

FIG. 2 is a right side view thereof;

FIG. 3 is a left side view thereof;

FIG. 4 is a front view thereof;

FIG. 5 is a rear view thereof;

FIG. 6 is a top plan view of a second embodiment of the cycling shoe illustrated in FIG. 1, the only distinction being the configuration of the bottom surface, it being understood that all other surfaces are the same as those in the first embodiment;

FIG. 7 is right side view of FIG. 6;

FIG. 8 is left side view of FIG. 6;

FIG. 9 is front view of FIG. 6; and,

FIG. 10 is rear view of FIG. 6.

The broken line showing of the bottom surface of the cycling shoe is for illustrative purposes only and forms no part of the claimed design.
